UNITED STATES PATENT OFFICE.

CHARLES B. OVERBAUGH, OF NEW YORK, N. Y.

PULVERIZING CONDIMENT-HOLDER.

SPECIFICATION forming part of Letters Patent No. 737,267, dated August 25, 1903.

Application filed December 11, 1902. Serial No. 134,759. (No model.)

To all whom it may concern:

Be it known that I, CHARLES B. OVERBAUGH, a citizen of the United States, and a resident of New York, in the county of New York and State of New York, have invented certain new and useful Improvements in Pulverizing Condiment-Holders, of which the following is a specification.

The invention relates to improvements in pulverizing condiment holders or receptacles; and it consists in the novel features of construction and combinations of parts hereinafter described, and particularly pointed out in the claims.

15 The object of the invention is to produce a salt-cellar or like receptacle having efficient means for preventing the caking of the salt or other material therein and for insuring the proper discharge of the same through the 20 perforated top or cap of the receptacle.

A further object of the invention is to produce an efficient agitator for the interior of the holder or receptacle which will adapt itself to the varying diameters of such receptacle.

25 Difficulties have heretofore been experienced in the construction of rotary agitators for the interior of condiment-receptacles, due to the fact that when such receptacles are made of glass they frequently vary in depth and diameter even when intended to be of the same general size; and one purpose of my invention is to provide a rotary agitator which may be adapted to the varying conditions as to the interior of the receptacles.

30 A further object of the invention is to provide a rotary agitator for condiment holders or receptacles which during use will not likely become coated with the substance contained in the receptacle, there being provided in accordance with my invention a weight which during the shaking of the receptacle will so vibrate or jar the agitator as to prevent the accumulation thereon of the substance contained within the receptacle.

45 The invention will be fully understood from the detailed description hereinafter presented, reference being had to the accompanying drawings, in which—

Figure 1 is a central vertical section through a salt-cellar constructed in accordance with and embodying the invention. Fig. 2 is a bottom view of the cap of the receptacle with

my attachment applied thereto, the body of the receptacle being omitted. Fig. 3 is an enlarged edge view, partly broken away, of 55 my attachment for the receptacle. Fig. 4 is a central vertical sectional view of same on the dotted line 4 4 of Fig. 5. Fig. 5 is a horizontal section of same on the dotted line 5 5 of Fig. 4, and Fig. 6 is a side elevation of a 60 slightly-modified form of rotary agitator.

In the drawings, 10 designates the receptacle for salt or other material, and 11 the perforated cap therefor, the latter being usually threaded upon the upper end or neck of the 65 receptacle.

The features comprising my invention pertain not so much to the receptacle 10 or cap 11 as to what may be termed an "attachment" for the receptacle, this attachment comprising a tubular rod 12, extending freely through a central aperture in the cap 11 and carrying the horizontal spider-frame 13 and suspended agitator-frame 14, while within the tubular rod 12 is confined a movable weight 15, which 70 during the shaking of the receptacle 10 may reciprocate between the closed ends of said rod 12. The tubular rod 12 is preferably formed of two telescopic sections 16 17, and within these sections 16 17 is formed a chamber 75 within which is confined the movable weight 15. The sections 16 and 17 are prevented from turning axially upon each other by reason of the fact that one of said sections is formed with a small lug 18, adapted to be 80 confined within a vertical groove 19, formed in the other of said sections, the purposes of said lug and groove being to prevent during the axial rotation of the attachment the turning of the section 16 within the section 17 and 85 to permit of a proper telescopic action of said sections with respect to each other when required. The section 16 extends upwardly through the central aperture in the cap 11 and is formed with an annular bead 20, upon 90 which the spider-frame 13 may rest, said spider-frame 13 being, as illustrated in Fig. 1, close up under the lower surface of the cap 11 and being rigid with the section 16, so as to rotate therewith when the section 16 is 95 given an axial motion. The section 17 fits upon the lower portion of the section 16 and is below the cap 11 and spider-frame 13, and this section 17 at its lower end is slotted to

100

receive the upper transverse bar 21 of the agitator-frame 14, the latter being carried by and rigid with the said section 17 and the said bar 21 being exposed to the action of the 5 weight 15 during the reciprocation of the latter when the receptacle is shaken, as herein-after explained.

The spider-frame 13 will preferably be formed by being stamped out of sheet metal 10 and is equipped with radial fingers or members, as shown in Fig. 2, extending close below the lower surface of the cap 11, and this frame 13 will during the axial turning of the rod 12 clear the lower surface of said cap and 15 facilitate the exit of the salt or other material through the perforations thereof.

The agitator-frame 14 is formed from a single rod of wire whose middle portion constitutes the transverse bar 21, from one end of 20 which the wire is bent downwardly to form the member 22, thence laterally to form the bottom member 23, and thence upwardly to form the side member 24, while from the other end of said transverse bar 21 the wire 25 is carried downwardly to form the vertical member 25, thence laterally to form the lower member 26, and thence upwardly to form the side member 27, said members 24 27 being in close relation to the inner side walls of the 30 receptacle 10, while the members 23 26 are in close proximity to the inner surface of the bottom of said receptacle 10, as shown in Fig. 1. The members 22 25 are in the nature of springs and they permit the members 24 27 35 of the agitator-frame to be pressed inwardly toward each other when the attachment is being inserted into the receptacle 10, the said side members 24 27 being thus adaptable to the varying diameters of the interior of receptacles 10. The lower members 23 26 of the agitator-frame are not fastened together, and hence may move upon each other as the side members 24 27 are moved toward or from each other. It is desirable also that the agitator-frame 14 may be capable of vertical adjustment, because it is found when the receptacles 10 are made of glass that the thickness of the bottom of same varies considerably, and it is for this reason that I form the tubular rod 12 of telescopic or adjustable sections 45 16 17, so that, for illustration, should a receptacle 10 have a bottom less in thickness than that illustrated in Fig. 1 said rod 12 may be extended vertically, so that the lower members 23 26 of the agitator-frame may reach the lower end of the receptacle. The agitator-frame is thus adaptable to the varying conditions of the interior of the receptacles 10 and is rendered capable of engaging both the sides 50 and bottom of same.

In the employment of my invention it will be obvious that upon turning the tubular rod 12 axially the frame 13 will clean the lower surface of the cap 11 and that the agitator-frame 14 will pass through and loosen up the salt or other material contained within the receptacle. Upon the shaking of the recep-

tacle for the purpose of discharging the contents therefrom in the usual manner the weight 15 will be reciprocated within the tubular rod 12 and will strike the opposite ends of the same, thereby facilitating the clearing of the apertures in the cap 11 and the discharge of the contents of the receptacle through said apertures. The movement of the weight 15 is important also because it will jar the wire agitator-frame 14 and loosen any salt or other material therefrom, thereby preventing the said agitator-frame from becoming incrusted. The movement of the weight 15 is also important because should the agitator-frame 14 when placed within the receptacle 10 not reach the bottom of the same the striking of said weight against the transverse bar 21 of said frame will operate to move 75 said frame to its extreme position, causing the section 17 of the tubular rod 12 to slide outwardly upon the section 16 of said rod, said rod 12 thus becoming extended, so as to enable the lower members of the agitator-frame 14 to reach the bottom of the receptacle. 80

In Fig. 1 the inner side walls of the receptacle 10 are slightly tapered, and the side members 24 27 of the agitator-frame are thus on downwardly-converging lines adapting themselves to the inclination of the walls of the receptacle; but some salt-cellars and other receptacles have a somewhat globular or elliptical interior, and for such receptacles the side members 24 27 of the agitator-frame 14 90 will be given a general curved outline, as illustrated in Fig. 6, so as to adapt them for the inner side walls of such receptacles. 95

The confining of the weight 15 within the tubular rod 12 is of advantage in several respects, one being that it does not disfigure the attachment, another that it is excluded from contact with the substance that may be discharged from the receptacle 10 during the shaking of the latter, and another that it permits of the employment of a tubular rod 12, having smooth surfaces of a diameter enabling the ready axial turning of the entire attachment. The confining of the weight 15 within the tubular rod 12 also enables said weight at one end of its stroke to effectually jar the agitator-frame 14 without striking the cap 11. 100

What I claim as my invention, and desire to secure by Letters Patent, is— 105

1. The receptacle having the perforated cap, combined with the tubular rod extending through said cap, an agitator-frame carried within said receptacle by said rod, and the movable weight confined within said rod; substantially as set forth. 110

2. The receptacle having the perforated cap, combined with the tubular rod, extending through said cap, an agitator-frame carried within said receptacle by said rod, the frame 13 carried by said rod above said agitator-frame, and the movable weight confined within said rod; substantially as set forth. 115

3. The receptacle having the perforated cap,

combined with the tubular rod extended through said cap, the frame 13 carried by said rod below said cap, and the movable weight confined within said rod; substantially as set forth.

4. The receptacle having the perforated cap, combined with the tubular rod of telescopic sections extending through said cap, an agitator-frame carried within said receptacle by said rod, and the movable weight confined within said rod; substantially as set forth.

5. The receptacle having the perforated cap, combined with the tubular rod extending through said cap and formed of telescopic sec-

15 tions equipped with means for preventing said sections from turning one upon the other, an agitator-frame carried within said receptacle by said rod, and the movable weight confined within said rod; substantially as set forth.

20 6. The receptacle having the perforated cap, combined with the rod extending through said

cap for manual operation, and the agitator-frame 14 carried by said rod within said receptacle and comprising the parallel separated vertical spring members 22, 25 extending 25 downwardly at opposite sides of the vertical center of the receptacle, the lower horizontal members 23, 26 extending laterally in opposite directions from the lower ends of said members 22, 25 respectively to the opposite 30 sides of said receptacle, and the spring members 24, 27 extending upwardly along the walls of said receptacle from the outer ends of said members 23, 26 respectively; substantially as set forth.

Signed at New York, in the county of New York and State of New York, this 9th day of December, A. D. 1902.
